UNITED STATES PATENT OFFICE

FREDERIK BERNARD, OF SAN FRANCISCO, CALIFORNIA

SAFETY VENTILATOR FOR OIL TANKS

Application filed March 7, 1928. Serial No. 259,616.

My invention has for its object a safety ventilator adapted to fill the opening in an oil tank or the like and is especially adapted to prevent the accumulation of pressure or vacuum during the filling or emptying of such tanks or during the temperature changes and to prevent fire and the explosion of gases that may collect therein.

In the handling of hydrocarbon oils and distillates in bulk in closed containers there is usually a space unfilled by liquid at the top and at all times during filling or emptying of such tanks such a space exists within which volatile and explosive vapors collect and any flame or ignition in the vicinity thereof is apt to ignite said vapors through the manholes, hand holes or the like which are invariably provided to secure an equalization of pressure and for introducing measuring sticks, pipes, etc.

It is customary to provide such tanks or storage receptacles with a hand hole or vent hole at top to allow escape of explosive gases and especially an equalization of pressure, and my invention is directed to a closure means for such opening or openings which will admit of the transfer of air from the outside into the receptacle of the gases from the interior to the exterior of said vessel through my ventilator to maintain the internal pressure equal with the external and therefore prevent undue stresses on the walls of the receptacle; and at the same time to prevent any possible transfer of flame or ignition into the gas, vapor or inflammable contents that may be in the receptacle.

These objects I accomplish by providing a screen-like cage within which I maintain a fluid compartment and a diaphragm of sponge, fibrous material, asbestos or the like, forming minute interstices through which a flame or ignition will not be propagated.

This diaphragm is preferably maintained wetted from the said water compartment, thus insuring a wetted diaphragm of a considerable area having minute and tortuous passages through which any gas or vapors may freely pass in either direction but through which no flame or ignition can pass.

A preferable form of my invention is shown

and described in the accompanying drawing and specification.

In the drawing Fig. 1 is a plan view of one embodiment of my invention.

Fig. 2 is a vertical midsection of Fig. 1. 55

Fig. 3 is a vertical cross section through an oil tank or receptacle showing the device of Figs. 1 and 2 applied thereto and in operative position.

Throughout the figures similar numerals 60 refer to identical parts.

The numeral 1 indicates the top portion of a conventional oil tank or receptacle 2, having an opening therein through which is introduced my ventilator, an outer cage portion 65 of which is shown by the numeral 3 turned over and flanged at 4 and fitted with a perforated top member 5.

At 6 is a fluid compartment into which dips the absorbent material shown at 7 and which latter extends above the fluid contents 8 and is supported by the member 9 so that by capillary attraction the fluid in the compartment 6 maintains the material 7 above the bar 9 saturated with fluid. 70

The compartment 6 is spaced from the cage 3 and the bar 9 horizontally spaced below the top 5 provides a chamber within which a sponge or similar absorbent material is filled as shown at 10. 75

The fluid 8 through the absorbent wick or fibrous material 7 therefore saturates the sponge 10 which is kept wet with the fluid.

A fine screen 11 preferably covers the sponge material 10 below the perforated top 85 member 5.

A gasket is shown at 12 sealing the space between the ventilator and the top 1 of the tank 2 with a conventional handle at 13 to lift the ventilator out when required. 90

The top 5 is locked to the flange 4 as by the bayonet lock members 14 and buttons 15.

The absorbent material 7 is preferably weighted as with the ring 20 to insure its contact therewith at all times as the fluid 8 95 evaporates.

Cage 3 is perforated as at 16, 16, 16 and also at the top as at 17, 17 thus enabling air, gas or vapors which may collect in the space 18 to pass freely through the holes 16 spaced 100

between the cage 3 and compartment 6 as shown at 19, through the sponge or other diaphragm 10 thence through the screen 11 and opening 17 in the top or cover 5 to the outside 5 of the tank 2 or vice versa and thereby equalize and maintain equalized the pressure between the space 18 and the surrounding air.

During the said passage the vapors are forced through the wetted surfaces of the 10 interstices in the diaphragm member 10 which functions to prevent the passage of any flame or ignition therethrough.

It will now be understood that my invention may be embodied in other forms than 15 that shown in the drawing and specification without departing from the spirit of my invention and I wish to be understood as claiming all such.

I claim:

20 1. As an article of manufacture a safety ventilator comprising a multiperforated cage, a fluid chamber fixed in suspended position within said cage, a perforated cover for said cage and spaced from said chamber, absorb- 25 ent material within the cage and between the chamber and the cover and communicating with the interior of said chamber.

2. As an article of manufacture a safety 30 ventilator comprising a multiperforated cage, a fluid chamber fixed in suspended position within said cage, a perforated cover for said cage and spaced from said chamber, absorb- 35 ent material within the cage and between the chamber and the cover and communicating with the interior of said chamber, a flange and gasket adapted to support said ventilator within an opening.

3. As an article of manufacture a safety 40 ventilator comprising a multiperforated cage, a fluid chamber fixed in suspended position within said cage, a perforated cover for said cage and spaced from said chamber, absorb- 45 ent material within the cage and between the chamber and the cover, a wick communicat- ing with the interior of said chamber and in capillary control with said absorbent mate- rial.

4. As an article of manufacture a safety 50 ventilator comprising a multiperforated cage, a fluid chamber fixed in suspended position within said cage, a perforated cover for said cage and spaced from said chamber, absorb- 55 ent material within the cage and between the chamber and the cover, a wick communicat- ing with the interior of said chamber and in capillary control with said absorbent mate- rial, a flange and gasket adapted to support said ventilator within an opening.

5. A safety ventilator comprising a perva- 60 ous cage and a pervious cover for said cage, means for detachably holding said cover as- sembled with said cage, a chamber fixed within and spaced from said cage and from said cover and having a top opening, absorbent 65 material pervious to vapors forming a dia-

phragm between the cage and the cover and in capillary communication with the interior of said chamber.

6. A safety ventilator comprising a pervious cage and a pervious cover for said cage, 70 means for detachably holding said cover as- sembled with said cage, a chamber fixed with- in and spaced from said cage and from said cover and having a top opening, absorbent 75 material pervious to vapors forming a dia- phragm between the cage and the cover, a wick communicating with the interior of said chamber and in capillary contact with said absorbent material.

FEDERIK BERNARD.
